[57] CLAIM

The ornamental design for a notebook computer housing, as shown and described.

DESCRIPTION

FIG. 1 is a top plan view of the notebook computer housing showing my new design with the display in the closed position;

FIG. 2 is a top plan view thereof with the display in a second orientation with the screen exposed;

FIG. 3 is a bottom plan view thereof;

FIG. 4 is a front elevational view thereof in a closed position;

FIG. 5 is a rear elevational view thereof;

FIG. 6 is a left side elevational view thereof;

FIG. 7 is a right side elevational view thereof;

FIG. 8 is a top plan view of the notebook computer housing with the display in an open position;

FIG. 9 is a front elevational view thereof;

FIG. 10 is a rear elevational view thereof;

FIG. 11 is a left side elevational view thereof; and,

FIG. 12 is a left side elevational view thereof, shown with the display oriented in an alternate position.
